UNITED STATES PATENT OFFICE.

WILLIAM C. DOWNEY, OF WASHINGTON, DISTRICT OF COLUMBIA.

DESIGN FOR AN ATOMIZER.

SPECIFICATION forming part of Design No. 31,892, dated November 28, 1899.

Application filed November 2, 1899. Serial No. 735,637. Term of patent 14 years.

To all whom it may concern:

Be it known that I, WILLIAM C. DOWNEY, a citizen of the United States, residing at Washington, in the District of Columbia, 5 have invented a certain new and useful Design for an Atomizer; and I do declare the following to be a full, clear, and exact description of the invention, such as will enable others skilled in the art to which it appertains to 10 make and use the same, reference being had to the accompanying drawings, and to the letters of reference marked thereon, which form a part of this specification.

This invention relates to a certain new and 15 useful design for atomizers, of which the following is a specification, reference being had to the accompanying drawings, which form a part of this specification, and in which drawings—

20 Figure 1 is a perspective view of an atomizer embodying my design. Fig. 2 is a central vertical section taken through the body portion of the atomizer, with the nozzle shown in full lines in side elevation. Fig. 3 is a like

view taken at right angles to the plane upon 25 which Fig. 2 is taken.

As shown in the drawings, the leading or essential features of my design consist of a substantially egg-shaped body portion A, having one of its sides flattened, as shown at B, 30 the opposite face or side of the body portion being provided with a convex, elliptical, or egg-shaped portion C. At the upper end of the body portion is shown an acorn-shaped extension or nozzle D, at the apex of which 35 is shown a second acorn-shaped extension E.

Having thus described my invention, what I claim to be new, and desire to secure by Letters Patent, is—

The design for an atomizer, substantially 40 as herein shown and described.

In testimony whereof I affix my signature in presence of two witnesses.

WILLIAM C. DOWNEY.

Witnesses:
